UNITED STATES PATENT OFFICE.

PERCY W. HODGKINSON, OF ROCHESTER, NEW YORK.

WRENCH.

1,172,797.

Specification of Letters Patent. Patented Feb. 22, 1916.

Application filed November 8, 1915. Serial No. 60,427.

To all whom it may concern:

Be it known that I, PERCY W. HODGKINSON, a citizen of the United States, and resident of Rochester, in the county of Monroe 5 and State of New York, have invented certain new and useful Improvements in Wrenches, of which the following is a specification.

The object of this invention is to produce 10 a wrench which may be conveniently used to hold a bolt against rotation while the nut is being removed therefrom, or to hold the nut while the bolt is being removed, in locations where access to the bolt or nut 15 with an ordinary wrench or spanner is inconvenient, or where the arrangement of parts is such that it is inconvenient for one person to manipulate simultaneously the two wrenches required for rotating one member 20 and holding the other.

To the foregoing end I employ a wrench which comprises a head, formed as a socket or otherwise, which is adapted to receive the bolt-head or the nut, and means connected 25 with or attached to this head and adapted to engage adjacent stationary parts or bodies, so as both to hold the head of the wrench in engagement with the nut or the bolt-head, and to prevent rotation of the 30 wrench. Since the invention is adapted particularly for use in connection with bolts or nuts which are accessible only from beneath certain parts of an automobile, the means for holding the wrench in engagement with 35 the nut or the bolt are arranged, in the preferred embodiment of the invention, to extend to and engage the floor-surface or ground beneath the automobile, while the means for preventing rotation of the wrench 40 have the form of a lug or projection adapted to engage a part of the automobile which is located alongside the bolt.

Other features of the invention will be set forth hereinafter, in connection with the description of the wrench illustrated in the accompanying drawings.

In the drawings:—Figure 1 is a side-elevation of a wrench embodying the present invention; Fig. 2 is an elevation, partly in 50 vertical section, looking from left to right in Fig. 1; Fig. 3 is an end-view of the wrench; and Fig. 4 is a view showing the manner in which the wrench is used in con-

nnection with an automobile, of which certain parts only are shown.

The invention is illustrated as embodied in a wrench of which the head is in the form of a socket 5 adapted to receive and hold a nut or bolt-head and to prevent rotation thereof. Extending integrally from one 60 side of the head is a lug 6, which prevents rotation of the head as hereinafter described. A downwardly-extending shank 7, integral with the head 5, is longitudinally bored to receive a stem 8 in the form of a round rod, 65 which slides freely in the shank. A compression-spring 9, inclosed within the shank, tends to force the stem outwardly, and this movement of the stem is limited by a pin 70, which is fixed transversely in the stem and 70 arranged to slide in vertical slots in the shank.

Fig. 4 shows the manner in which the wrench is used in removing or replacing the bolts which connect the upper and lower 75 members of the crank-case of the engine in an automobile. Such bolts, at least as employed in certain well known automobiles, are impossible of access by one person simultaneously from above and below, so that in 80 manipulating them the services of two persons are usually required. With the present wrench, however, the services of one person may be dispensed with. For this purpose the stem 8 of the wrench is engaged with 85 the floor-surface directly beneath the bolt which is to be removed or replaced, and the head and shank are then pressed downwardly, thus compressing the spring 9, so that they may be passed beneath the nut or 90 the head of the bolt, as the case may be, and then allowed to rise so as to bring the head 5 of the wrench into engagement with the nut or bolt. The wrench will then automatically retain itself in that position, and 95

when an ordinary wrench is applied to the upper end of the bolt, or the nut thereon, rotation of the lower member is prevented by engagement of the lug 6 with the adjacent surface of the crank-case. When the 100 bolt has been entirely unscrewed the lower member, whether the bolt itself or the nut, is held by the wrench, and does not fall to the floor or the road-surface.

If it be desired to place the bolt in the 105 crank-case with the nut on the upper end

of the bolt, the wrench of the present invention has the further advantage that it will hold the bolt in place, in the hole in the crank-case, while the nut is being placed upon the upper end of the bolt.

While I have described my wrench as particularly adapted for use in connection with the bolts used in a particular place in an automobile, it will be apparent that the invention is not limited to that embodiment, but may be embodied in various other forms, within the nature of the invention as it is defined in the following claims, according to the particular location and surroundings of the bolt which is to be acted upon.

I claim:—

1. A wrench comprising a head adapted to fit and hold a non-circular bolt head or nut; and means adapted to engage adjacent stationary bodies and retain the head against rotation and in engagement with the bolt or nut.
2. A wrench comprising a head adapted to hold a bolt or nut; a projection, from the head, adapted to engage a stationary body

Washington, D. C."

adjacent the bolt and to prevent rotation of the head; and adjustable means for engaging another stationary body to retain the head in engagement with the bolt or nut.

3. A wrench comprising a head adapted to fit and hold a non-circular bolt-head or nut; an elongated body extending directly away from the head and adapted for engagement with a stationary surface opposite the bolt-head or nut, to retain the head in engagement therewith; and a lateral projection, from the head, to engage an adjacent stationary body and prevent rotation of the head.

4. A wrench comprising a head adapted to fit and hold a non-circular bolt-head or nut; an elongated body extending directly away from the head and adapted for engagement with a stationary surface opposite the bolt-head or nut, the body comprising two members relatively movable to vary the length of the body; and a lateral projection, from the head, to engage an adjacent stationary body and prevent rotation of the head.

PERCY W. HODGKINSON.
